UNITED STATES PATENT OFFICE

HARRY S. JONES, OF CHICAGO, ILLINOIS

SHEET-HANDLING TRAY

Application filed September 20, 1923. Serial No. 663,772.

This invention relates to a universal loose sheet handling device or tray, which is designed to cooperate with any form of binder for machine book posting or for assorting, collecting and alining loose sheets.

It is an object of this invention to provide a posting tray which is considerably shortened so as to reduce the necessary reach of a person that is posting, which can be readily converted from one form to another and which may be easily collapsed for shipping, and which can be used for a sheet assorting, collecting and alining device.

With these and other objects in view which will become more apparent in the following description and disclosures in the drawings, this invention comprises the novel structure and combinations hereinafter described and more particularly pointed out and defined in the appended claim.

In the accompanying drawings which illustrate certain preferred forms of this invention and in which similar reference numerals refer to similar features in the different views.

Figure 1 is a side elevational view of the posting tray and binder.

Figure 2 is a view similar to Figure 1 showing an attachment applied thereto.

Figure 3 is a side elevational view of the tray with the sheet aliner attached.

Figure 4 is a top plan view of the tray in collapsed form.

Figure 5 is a top plan view of the tray shown in Figure 2.

Figure 6 is a top plan view of the tray shown in Figure 3.

Figure 7 is an enlarged view upon the line 7-7 of Figure 1 showing parts in section.

Figure 8 is a section on the line 8-8 of Figure 2.

Figure 9 is a fragmentary plan view taken upon the line 9-9 of Figure 3.

Figure 10 is an enlarged fragmentary plan view of the sheet aliner showing its attachment to the frame.

Figure 11 is a sectional view upon the line 11-11 of Figure 10.

In the illustrated form of this invention there is shown a collapsible frame having

supports for sustaining loose leaves. These supports are removable so that the structure may be collapsed; one of these supports is an alining support which may take different forms according to the sheet that is being handled.

In the illustrated form, the frame comprises a pair of side members preferably formed from flat metal bars consisting of base portion 1 and integral upwardly extending vertical portions 2 which curve inwardly at their upper ends and then incline downwardly to form inclined lateral supports 3. The lower ends of these inclined supports extend to the base portions 1 to which they are rigidly attached in any well known way. It will be understood that each pair of similarly inclined supports 3 constitutes one lateral support for the sheets.

A pair of crossed braces 4 are secured to the base portions of the side frame members. These braces are pivotally connected to one frame member and releasably connected to the other frame member. While any form of releasable connection may be used, I have shown releasable screws or bolts 5 for releasably connecting said crossed braces with one of said frame members. The inclined supports 3 may be braced in a similar way to the base portions and in the drawing I have shown crossed braces 6 applied to one pair of the inclined supports. These braces are pivotally connected to one inclined support and releasably connected to the other inclined support by means of removable screws or bolts 7. By removing the screws 5 and 7 the two side frame members may be collapsed as shown in Figure 4.

V shaped metal members 8 are attached between the inclined supports 3. Preferably these metal members are provided with attaching feet which are bolted or secured to the inclined supports. These metal members co-operate with the inclined supports 3 to form the well known W rack. Removable base supports 9 and 10 in the form of metal plates rest upon the inclined sides of the members 8. The outer ends of these plates are cut away as indicated at 11 (Figs. 5 and 6) so as to provide recesses for receiv-

ing the inclined lateral supports 3 whereby the said plates are retained against endwise movement but are capable of being readily lifted from their supports. The upper portion of the plate 9 overlaps the upper edge of the plate 10. In having one supporting plate as 9 overlapping the other plate, the lateral supports 3 are brought closer together so that the person using the tray will not have so far to reach across the tray. This is a very desirable and important feature in the use of such a posting tray.

The removable support 10 is provided with a sheet alining rib 12 which is suitably positioned to receive the impaling slots in the loose leaves as they are transferred from the support 9 to the support 10. In the form of the invention shown in Figure 1 and 2, it is contemplated that the loose sheets have open impaling slots.

When it is desired to use loose sheets with closed slots or apertures, the sheet supporting and alining plate 10 is removed, and the V shaped aliner 13 is secured upon the frame 25 of the tray. This V shaped aliner comprises a pair of side plates which converge to a point where the same are removably hinged together as by bent lugs 14 (Figure 9) on one passing through the other. A pair of 30 abutments 15 in the form of angle clips having their opposite surfaces converging similar to the convergence of the aliner are secured upon the braces 4, for supporting the lower end of the aliner 13. The upper 35 ends of the side plates of the aliner are provided with downwardly bent exterior ears or flanges 16 which are adapted to be removably secured to the inclined lateral supports 3, whereby the aliner is sustained in inclined position so that the loose sheets can be readily dropped therein and automatically aline themselves as they descend. The converging side plates of the aliner are provided with inwardly directed interior flanges 40 17, at their lower ends for supporting one of the covers of the posting ledger when one is used. One of these flanges has a cut away portion to receive the impaling posts when the binder is assembled in the aliner. 45 When the device is used for assorting sheets, letters or the like, any stiff piece of cardboard may be positioned in the aliner to form a support for the collected and alined sheets.

One of the uses to which the tray is especially adapted is that of machine book posting, and for this purpose posting tray binders have been illustrated in connection with the posting trays. In Figures 1 and 2, is 50 illustrated a binder in which the loose sheets have open impaling slots. The back or bottom cover 18 of the binder is shown resting upon the support 9 and the top cover 19 is shown resting upon the support 10. These 55 covers of course incline against the lateral

supports 3, and if it is desired to vary this inclination of the binder covers to a steeper inclination, spacing attachments 20 are adapted to be removably secured on the inclined lateral supports 3. These spacing attachments 20 are provided with hoods 20^a that frictionally engage over the bends of the supports 3, and downwardly extending shanks 20^b that are removably secured by clips or clamps 21 to the inclined portions 3 of the lateral supports. It is therefore evident that by adjusting the hoods through their frictional engagement with the supports 3 it is possible to vary the inclination of the binder covers which rest thereagainst. In connection with this form of the invention, it is obvious that as the loose leaves are transferred from the support 9 to the support 10 and positioned thereon with a slot engaging the alining rib 12 as shown in Figure 7, the loose sheets may be automatically alined as positioned thereon.

In Figure 3, is illustrated a binder in which the loose sheets have closed impaling holes. In this instance, the sheets are removed from the impaling posts, the bottom back 21 of the binder being positioned upon the ledger support 9 with its clamping member 22 which supports said posts dangling over the sides of the lateral support 3. The top cover 23 is shown positioned in the aliner 13. This form of the invention is especially adapted for random posting since the loose sheets on the ledger support are not retained upon any impaling posts but are free to be manipulated so that any sheet thereof may be quickly located and removed. Accordingly, one or more sheets may be readily removed from the ledger support 9 and dropped into the aliner 13 which automatically collects and alines the same.

Where it is desired to ship the tray, the same may be readily collapsed by releasing the connections of the braces 4 and 6 with one of the side frame members, removing the plates 9 and 10, or the plate 9 and the aliner 13 if the same is used, and pressing the frame members together as shown in Figure 4 whereby the cross braces will be folded therebetween. The supporting plates 9 and 10 may be confined between the two frame members. The aliner 13 may be disassembled to constitute two plates 13^a and 13^b as shown in Figure 4 which can be positioned alongside the frame members or therebetween so a compact form for shipping purposes may be attained.

From the foregoing it will be apparent that a novel form of tray for handling loose sheets has been devised which is shortened so as to reduce the necessary reach of a person in using the same for posting purposes, which automatically alines the sheets, and which can be easily collapsed for shipping purposes.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

In a posting tray, a pair of transversely spaced side members each member having a pair of inclined portions, inverted V-shaped rest members secured to the inclined portions of each member, an alining member of V-shaped trough form mounted on the said inclined portions and having its apex extending downward between said rest members, and a pair of members carried on said tray below said rest members and having converging surfaces adapted to receive the sides of the alining member adjacent its apex.

In testimony whereof I have hereunto subscribed by name.

HARRY S. JONES.
